UNITED STATES PATENT OFFICE

147,458

DESIGN FOR A FOLDING TOP FOR MOTOR VEHICLES

August Keller, Dearborn, Mich.

Application November 3, 1945, Serial No. 123,436

Term of patent 14 years

(Cl. D14—27)

To all whom it may concern:

Be it known that I, August Keller, a citizen of the United States, residing at Dearborn, Wayne County, Michigan, have invented a new, original, and ornamental Design for Folding Top for Motor Vehicles, of which the following is a specification, reference being had to the accompanying drawing, forming a part thereof, in which:

Fig. 1 is a side elevational view of a folding top for motor vehicles showing my new design;

Fig. 2 is a top plan view;

Fig. 3 is a rear elevational view;

Fig. 4 is a top perspective view thereof, as seen from the front and side;

Fig. 5 is a side elevational view showing the top as it would appear in a partially folded position; and

Fig. 6 is a side elevational view thereof as the top appears in fully folded position.

In all figures the dot and dash line showing of portions of a conventional motor vehicle body is for illustration purposes only.

I claim:

The ornamental design for a folding top for motor vehicles, as shown and described.

AUGUST KELLER.
